WAVE TRANSLATING METHOD AND CIRCUITS

Justin L. Fearing, Scarsdale, N. Y.

Application November 13, 1936, Serial No. 110,766

25 Claims. (Cl. 250—36)

This invention relates to methods of translating electrical energy into impulses or alternating current and to apparatus and circuits employed in connection with these methods. The invention makes use of space discharge apparatus of the type employing a deflectable beam of electric carriers.

Oscillators of the space discharge type commonly have the limitation that only a relatively small range of frequencies can be produced while using a given frequency determining standard, such as a resonant circuit. When frequencies above that range are to be produced, it is necessary to substitute a different frequency determining standard in the circuit or to resort to cascade harmonic producers. A cascade harmonic producer ordinarily requires one or more tuned circuits in addition to that for the fundamental frequency. It also suffers the limitation that when a sine wave of frequency, f , is subjected to a single harmonic producing operation, the harmonic components of frequencies $2f$, $3f$, and higher frequency, are of much smaller amplitude than that of the fundamental frequency f . Furthermore, the harmonic components of progressively higher frequency are of successively smaller amplitude.

An object of the present invention is to simplify the production of impulses and alternating currents of constant fundamental and harmonic frequency over a wide range of frequencies and to improve the efficiency of production of such impulses and currents.

Another object is to generate impulses or alternating currents over a wide range of frequencies under the control of a single frequency determining standard, and to produce very high frequency impulses and currents under the control of a frequency standard of lower frequency.

Another object is to utilize a periodically deflecting beam of electric carriers to commutate electric current in a single operation at a frequency equal to or higher than that of the positive and negative peaks in a wave controlling the deflection of the beam, and to derive the control wave from the deflecting beam.

Other objects are to restrict the production of and the amplitude of undesired harmonics, to reduce the number of tuned circuits required to control the production of higher harmonics of a fundamental wave, and to simplify the requirements of frequency determining circuits.

According to one aspect of the present invention, a beam of electric carriers is periodically deflected over a predetermined path including

commutator segments arranged and connected in such relation to the path that the discharge current may be simultaneously commutated at more than one frequency. The cyclic deflection of the beam may be maintained by waves derived from the resulting impulses or from an independent source.

According to another feature, the beam may trace a cyclic path in which less than all of one set of alternate segments are connected to one output circuit for the production of current of the frequency which maintains the cyclic deflection of the beam while the beam is at the same time commutating current at a different frequency for another output circuit.

According to another aspect of the present invention, the beam is deflected over any one of a plurality of rows of commutator segments to control the distribution of current impulses in the output circuit connections of the segments. The number of segments in any row may be sufficient to make the commutation frequency many times that of the deflection frequency. Different rows may contain different numbers of segments, and provision is made for selecting a deflection path over any desired row to determine the output circuit over which impulses are to be transmitted, or to determine the frequency of the impulses. When the beam has a given deflection frequency, any one of a plurality of different output frequencies may be produced, the output frequency in any case depending upon the deflection frequency and upon the effective number of segments in the row over which the beam is deflected. Frequencies in the range between the frequencies produced by different rows may be obtained by selecting harmonics produced within this range while the deflection frequency remains unchanged, or by adjusting the deflection frequency to produce commutation or harmonics at the desired frequency.

These and other features of the invention will be understood from the following detailed description in connection with the accompanying drawing illustrating specific applications of the invention.

In the drawing, Fig. 1 is a diagram of one form of space discharge device and the circuit thereof for producing electrical impulses and alternating currents of fundamental and harmonic frequencies.

Fig. 2 is a diagrammatic radial face view of the commutator of Fig. 1.

Fig. 3 is a radial face view of a supporting disk for the commutator.

Fig. 4 is a fragmentary view of an axial section of the commutator end of the space discharge device of Fig. 1, showing in detail the arrangement for supporting the commutator and an axial section of the Fig. 3 disk, taken on the line 4-4 of Fig. 3.

Fig. 5 is a diagram of circuit connections for the commutator of Figs. 1 and 2.

Figures 6 to 10 are diagrams of modified forms 10 of commutators and output connections.

Referring to Fig. 1, the space discharge device 1, consisting of a highly evacuated tube, preferably of transparent glass, contains the heater 2 for the cathode 3 which in turn is adapted 15 when the tube is suitably energized to discharge an electron stream through the axial apertures of the annular control electrode 4 and the annular anode 5, thereby producing a beam of electrons which discharges through the space 20 between the beam deflecting electrodes 6, 7, 8, 9. The commutator 10 serves as a target for receiving the electron beam, and is supported from the end wall 12 of the neck 13 having the 25 flare 14 joined with the main wall of the tube 1, the elements 12, 13, 14 forming a reentrant end for the tube.

One pair of deflecting electrodes 6, 7 are disposed face to face with each other on opposite 30 sides of the tube axis, on a diameter of the tube at right angles to the diameter on which the deflecting electrodes 8, 9 are disposed face to face with each other on opposite sides of the tube axis. Electrodes 8, 9 may be spaced slightly further along the tube axis from the cathode 3 than electrodes 6, 7.

Electrodes 6 to 9 are constructed and arranged as in well known cathode ray oscilloscopes. It is 40 to be understood, however, that the electrodes and other parts of the tube may be varied in design in accordance with the well known technique of high frequency tubes when very high frequencies are to be utilized and in accordance with that of high power tubes when a larger amount of power is to be utilized than with an ordinary oscilloscope tube.

The commutator electrode 10, Fig. 2, is made up of a plurality of separate electrodes 15, 16, 17, 18, 19. The sectored disk 15, 16, the ring 50 17 and the ring 18, 19 have their electron receiving surfaces and their circular rims coaxial with the tube axis. The electron receiving surface of the commutator 10 may be in a radial plane of the tube, or may be of slight curvature, not shown, as in the case of the usual oscilloscope tube screen. The commutator may be 55 made of nickel, molybdenum, tungsten, or other suitable refractory metal. The disk 15, 16 and the ring 18, 19 are divided into sections by the insulating radial gaps 25 which are on the same diameter in the Fig. 2 commutator.

While Fig. 2 shows the disk 15, 16 and two rings 17 and 18, 19, it will be understood that in its simplest form, the commutator may utilize only two rings 17 and 18, 19 without the disk or may utilize only one ring 17 and the disk 15, 16 without the other ring 18, 19, or may utilize only the disk 15, 16. Furthermore, the commutator 10 may include additional rings around those shown in Fig. 2, as shown diagrammatically in Fig. 6, for example, in which the added rings 21 and 22 are provided. Starting with the rim of the sectored disk 15, 16 which for convenience of description may be referred to as a 70 ring, and going radially outward, it will be noted

that one set of alternate rings consisting of the rim of disk 15, 16, ring 18, 19 and ring 21, 22, Fig. 6 are divided by gaps 25 into sections, while the intervening rings 17 and 20, constituting the other set of alternate rings, are closed without gaps 25.

Each of the adjacent edges of any two adjacent rings has teeth-like segments 26 projecting radially into the space between these edges. The segments 26 have such dimensions and locations 10 that those on one edge of a ring nest with uniform spacings between those on the adjacent edge of the adjacent ring, thus forming a single circular row of segments between each pair of adjacent rings and coaxial with the tube axis. 15 One set of alternate segments in any one row connects with one ring and the other set of alternate segments connects with the adjacent ring. The edges of each ring and its segments are spaced sufficiently from the edges of the adjacent ring and its segments to insulate the rings 20 from each other.

In order to obtain uniform frequency of commutation, the segments in any one row are as 25 nearly as possible of precisely equal width measured in a direction along an arc coaxial with the rings, and the spacings measured between adjacent segments along any such arc are made as nearly as possible precisely equal to each other. Each row preferably contains a different 30 number of segments from that of other rows. The number of segments in any row is preferably greater than that of a row of smaller diameter and less than that of a row of greater diameter.

The commutator 10 is supported from a disk 35 11 Figs. 1, 3, 4, of highly refractory porcelain, glass, or other material of suitably high mechanical and dielectric strength to serve as a support while heated moderately and while subjected to bombardment by an electric discharge. 40

Fig. 4 shows details of one of the supporting elements 38 for the ring section 18 of the commutator. Similar supports 38 are provided at other points along the ring 18, 19 and on the other rings at the places indicated by the small circles on the rings in Fig. 2. The concentric circles 31, 32, 33 on disk 11, Fig. 3, designate the center lines of the holes 34 from which the disk 15, 16, the ring 17, and the ring 18, 19, respectively are supported. In order to simplify 45 the drawing, the segments 26 of Fig. 2 are omitted from the ring section 18 in Fig. 4.

The support 38 consists of a wire parallel to the tube axis and firmly secured at one end to the ring 18 by passing through a hole therein and 55 having its outer end preferably welded or riveted to the ring. The wire 38 passes freely through the tubular metal spacer 35 and the hole 34 in the disk 11. At the end of the hole 34 remote from ring 18, the wire 38 is given a sufficiently sharp bend or offset 36 to hold the ring 18 securely in place in fixed relation with the disk 11 and to prevent objectionable looseness of the spacer 35 between the ring and disk. 60

The disk 11, as shown in Figs. 3 and 4, is supported by four equally spaced stiff wires 37 parallel to the tube axis. One end of each wire 37 passes freely through a hole 28 near the edge of the disk. The other end is sealed into the end 70 wall 12 of the neck 13 and may be employed as a lead-in wire. The short wires 38, 39, welded or otherwise firmly secured to the lead 37 at opposite sides of the disk 11, provide stops for limiting movement of the disk axially of the tube and 75

for holding the disk in its proper space relation with the end wall 12 of the tube.

Wires 38, 39 are preferably separated more than the thickness of the disk 11 at the hole 28, so that one or both of the outer ends of the wires may be bent axially of the tube into contact with the edges of the disk to adjust the position of the disk and to hold it securely in place without causing excessive stresses therein. This arrangement provides a simple and rugged form of anchorage for the disk 11, and is particularly adapted to yield to stresses originating from thermal and other causes.

Each ring and ring section, such as section 18, Fig. 4, is electrically connected with one of the lead-in supports 37 or with a separate lead-in wire 40 by a tie-wire 41. Various different connections between rings and sections thereof may be made, depending upon the kind of output circuits to be employed or upon the kind of output current desired. Several specific arrangements of output circuit connections for the commutator 10 are shown in Figs. 5 to 10. The direct connections between the rings may obviously be completed within the tube by tie-wires 41, Fig. 4, or may be outside of the tube.

The front surface of the commutator exposed to bombardment by the electron beam is preferably, but not necessarily, treated to reveal momentarily for visual observation, the area or path on the surface over which the beam travels. One such method is to deposit on the front surface of the disk 15, 16 and the rings 17, 18, 19, etc., a thin layer of condensed vapor of a refractory metal, such as molybdenum, in an atmosphere of low pressure inert gas, such as argon, to produce a finely divided metal film on the surface of the commutator. Another method is to coat the front surface of the commutator with a thin film of zinc orthosilicate, commonly known as synthetic willemite.

When assembling the commutator 10 and mounting it within the tube 1, the disk 15, 16 and rings 17, 18, 19, Fig. 2, are first assembled on the disk 11. A tie-wire 41 is attached to one support wire 30 for each commutator element. The neck 13 and flare 14 are as yet unattached to the main wall of the tube. The four support wires 37 and the desired number of lead-in wires 40 are sealed into the end wall 12 of the neck 13. The disk 11, carrying the commutator elements assembled therewith, is then mounted on the supporting wires 37, the wires 38, 39 being secured in position so that the commutator may be located coaxially of the tube, the free ends of the tie-wires 41 being connected with the proper lead-in wires 37 and 40. The neck 13 is then sealed at the flare 14 to the main wall of the tube 1 to form a reentrant end therefor, care being taken to locate the commutator and its front surface coaxially to the tube. Degassing of the elements within the tube, assembly of the other parts of the tube, and the other procedures of the usual type necessary for producing a high vacuum tube, are well understood by those skilled in the art, and need not be referred to in detail. While one specific method of supporting the commutator 10 has been described by way of illustration, it will be understood that various other forms of support may be employed.

The circuit connections for the tube 1, Fig. 1 will now be described. A source of alternating current energy 58 is provided for the heater 2 of the cathode 3. A conductor 51 extends from the heater 2 and cathode 3 to ground at 52 which

also connects with the battery 53 or other steady source of direct current energy having the adjustable voltage terminals 54, 55, 56, 57, 58, 59, 60. Terminal 55 is in the direct connection of the battery with ground 52. Terminal 56, connecting with the anode 5, is adjusted relatively to terminal 55 to provide a suitably high positive potential relatively to ground and to the cathode 3 to attract a stream of electrons toward anode 5. Terminal 54, connecting with the control electrode 4, is adjusted to a lower potential than anode 5 and may be either positive or negative relative to cathode 3, depending upon the adjustments of the potentials of the other electrodes and the characteristics of the tube. Terminals 54 and 56 are adjusted relatively to each other to control the concentration of the beam and cross-sectional area of the beam where it strikes the commutator 10.

The resistance elements 61 may be included in the leads of electrodes 4, 5, 6, 7, 8, 9 to prevent undesirably large currents from flowing to these electrodes.

The transformer 65, 66 has the upper and lower terminals of its secondary coil 66 connected, respectively with the deflecting electrodes 9 and 6. The deflecting electrodes 7, 8 connect, respectively, through the condensers 67 and 68 of negligibly low impedance, with the mid-point 69 of the impedance 70 shunting the coil 66. The impedance 70 includes the branched circuit 71, 72 in series with the branched circuit 73, 74. The circuit 71, 72 consists of the variable resistance 71 in parallel with the variable condenser 72, and the circuit 73, 74 consists of the variable resistance 73 in parallel with the variable inductance 74.

The combined impedance of elements 71, 72 is adjusted to be equal to that of elements 73, 74, while the ratio of the combined reactance to resistance of elements 71, 72 is adjusted relatively to the ratio of reactance to resistance of elements 73, 74, so that the phase angle between the voltage across the impedance 71, 72 and the voltage across the impedance 73, 74 is 90 degrees. The single phase voltage from the transformer 65, 66 is thus converted into a two phase voltage. The phase across elements 71, 72, is impressed on the deflectors 6, 7, while the phase across elements 73, 74, is impressed on deflectors 8, 9, thereby deflecting the forward end of the beam of electrons so that it rotates periodically through a circular path.

Adjustment of the terminals 57, 58, 59 of the battery 53, control the static potentials of the deflectors 6, 7, 8, 9 relatively to the anode 5 and the cathode 3, the potentials being so adjusted that the beam passes by the deflectors without being objectionably attracted or repelled by their static potentials. A path for the static potential of deflector 6 may be traced from the terminal 57, through the resistance 71 in parallel with another path through elements 73, 74 and coil 66. A path for the static potential of deflector 9 may be traced from the terminal 57 through elements 73, 74 in parallel with another path through the resistance 71 and coil 66. Adjustment of terminal 58 controls the steady potential difference between deflectors 6, 7, so that the circular path traced by the beam may be properly centered in a vertical direction. In a similar manner, adjustment of terminal 59 controls the potential difference between deflectors 8, 9 and permits of centering the circular path in a horizontal direction.

The circular path of the beam may thus be ad-

justed to a position coaxial with the tube and with the disk 15, 16 and the rings 17, 18, 19, and so on, of the commutator 10. The position of the path at any instant may be observed by watching the luminous path traced by the beam on the surface of the commutator, or by observing the current passing through the respective leads or circuits connecting with the different parts of the commutator.

10 Referring to Figs. 1 and 5, the output circuit 80, 62 of the tube connects the commutator ring 17 with the adjustable positive potential terminal 60 of the battery 53, and includes the output coupling 81, 82, consisting of the variable tuning condenser 81 in parallel with the inductance 82. The coupling 81, 82 may be tuned to resonance with the frequency of the desired output wave. Coupled with the inductance 82, is the inductance 83, connected with the utilization circuit 84, labelled UC.

15 The output conductor 85 connects with the right hand sector 16 of the disk 15, 16, and the right hand sector 19 of the ring 18, 19 and extends by way of the lower contact of the switch blade 86, when the two pole switch 86, 87 is in its lower position, to the cathode 89 of the current limiting device 90, having the anode 91 from which the path of the output current may be traced to the resonant frequency determining circuit 92, 93, consisting of the inductance coil 92 in parallel with the variable tuning condenser 93, and through the lower contact of switch blade 87, to conductor 85 and 62 to the battery 53.

20 The current limiter 90 may be a rectifier of the well known thermionic diode type, having its cathode heated to such a temperature by current from the battery 48 controlled by the variable resistance 49 that the space current increases rapidly with increase of the positive potential of the anode relatively to the cathode of the rectifier, but the space current quickly reaches a substantially constant predetermined strength or value which does not increase appreciably when the anode-cathode voltage of the rectifier increases further to considerably greater values corresponding with the maximum working voltages applied thereto. In other words the rectifier 90 becomes saturated at a voltage which is low compared with the usual maximum instantaneous operating voltages applied thereto. The rectifier 90 thus prevents the amplitude of the current supplied to the frequency determining circuit 92, 93 from departing from a predetermined value.

25 The resonant circuit 92, 93 is preferably of low-loss construction and is preferably sharply tuned. The circuit is also preferably arranged in well known manner to maintain its constants unchanged when the temperature in the vicinity thereof changes. Adjustment of the tuning is therefore primarily under the control of the variable condenser 93.

30 The left hand sector 15 of the disk 15, 16 and the left hand sector 18 of the ring 18, 19 are connected together with the conductor 96, in series with the variable resistance 97, the choke coil 98, and the conductor 92, connecting with the positive terminal 60 of the battery 53. Resistance 97 is adjusted to prevent an undesirably large current through the conductor 96. The choke coil 98 is of high impedance to alternating current of the deflection frequency or higher.

35 The inductance coil 99, variably coupled as a transformer secondary with the inductance coil 92, has its upper terminal connected through the adjustable phase controlling reactance 100, the

conductor 101, the upper contact of the switch 102, and the rheostat 103 in series, to the upper end of the potentiometer 104. The lower terminal of the coil 99 connects through the conductor 105 and the upper contact of the switch 106 with the lower end of the potentiometer 104. Two or more sliding contacts 107 on the potentiometer 104, each connecting, respectively, through one of the variable phase shifting reactances 108 and with one of the contacts of the sliding switch 109, 10 provide a connection between the potentiometer 104 and the upper end of the primary coil 65. The lower end of the potentiometer connects directly with the lower end of the coil 65.

40 The repeater or amplifier 110, labelled A, and adapted to repeat in the direction indicated by the arrow, has its input terminals 111, 112 connected across the conductors 101, 105, and its output terminals 113, 114 connected respectively, with the lower contacts of the two-pole switch 102, 106. The amplifier A may be of any well known type, adapted faithfully to reproduce at its output terminals, the wave impressed upon its input terminals, without introducing distortion.

45 The form of amplifier shown in the drawing is of the well known resistance-capacity coupled type, in which the low impedance blocking condenser 115 in series with the potentiometer resistance 116, is connected across the input terminals 111, 112, the sliding contact 117 for varying the amplification, being connected with the grid of the triode repeater or amplifier tube 118. The usual direct current source 119 is provided to polarize the grid negatively with respect to the 50 cathode for the purpose of reducing distortion. The anode-cathode circuit includes the resistance 120 in series with the source of space current 121, and transmits output waves through the low impedance blocking condenser 122 to the output terminals 113, 114 which are connected with the lower contacts of the switch 102, 106, in such phase as to provide the same instantaneous polarity for the potentiometer 104 as the upper contacts of the switch 102, 106. The amplifier A 55 may obviously consist of more than the one stage shown.

50 The repeater or amplifier 125, having its input terminals connected in parallel with those of the repeater 110, serves as unilaterial transmission device to transmit waves of the frequency selected by the tuned circuit 92, 93 to the utilization circuit 126 and to prevent reaction of the circuit 126 on the tuned circuit 92, 93.

55 The independent source of waves 130, is connected across the upper contacts of the switch 86, 87, so that when the switch is in its upper position, impulses are transmitted from the source 130, through the rectifier 90 to the resonant circuit 92, 93, in place of impulses transmitted over 60 conductors 85, 86 from the commutator 10. In this case the circuit 92, 93 is preferably tuned to the frequency of the source 130, but may be tuned to a harmonic thereof.

65 When operating the tube 1, the adjustable terminal 60 of the battery 53 is adjusted to such a positive potential relatively to the cathode 3 that the beam of electrons discharges on the commutator 10. The focus of the beam may be adjusted by varying the potentials of electrodes 4, 5. The static potentials of the deflectors 6, 7, 8, 9 are adjusted by terminals 57, 58, 59, as already referred to, so that the beam is suitably centered relatively to the commutator axis.

70 The current in the beam, builds up almost in- 75

stantly to its steady value for the particular adjustment of the tube and battery 53. Assuming at least a part of the beam current discharges through the sector 16, either because of the beam dividing its current between sectors 15 and 16, or because of the beam being directed wholly or in part upon sector 16 near the center of the disk 18, 16, an impulse of direct current derived from the battery 53 by way of cathode 3, discharges through the conductor 85, the current limiter 90 and the resonant circuit 92, 93, back through the conductor 85 to battery 53. Waves of resonant frequency are thus set up and stored in the frequency determining circuit 92, 93, and are transmitted from the secondary coil 99 of the coupling 92, 93, through conductors 101, 105, switch 102, 106 to the potentiometer 104, from which the waves are transmitted through the transformer 65, 66 and to the deflectors 6, 7, 8, 9, causing the beam to be deflected cyclically over a circular path which quickly increases in diameter to a fixed steady state value of constant frequency as impulses are supplied to the circuit 92, 93 in successive cycles.

For the production of the highest frequencies, the switch 108 is placed in its highest position with the highest slider 107 near to but somewhat short of its highest possible position. The resistance 103 is then adjusted until the control wave applied to the deflectors 6, 7, 8, 9, has sufficient amplitude to cause the beam to trace a path over the outermost row of segments 17, 18, 19, Figs. 2 and 5. The uppermost phase shifting reactance 108 may then be adjusted to establish the optimum output of waves of the deflection frequency, so that the beam strikes and removes from the ring section 19 at such instants of time that successive impulses of the deflection frequency produce the desired additive effect in the circuit 92, 93, or provide the desired stability of operation.

Adjustment of the resistance 103 may be necessary while adjusting the phase shifting reactance 108, in order to maintain the control wave at its proper amplitude, so that the beam may be kept traveling over the proper row 17, 18, 19. One half of one set of alternate segments, namely those on the edge of the sector 18, collect direct current during every other half cycle of the deflection wave. At the beginning of one half cycle, the beam passes from ring section 18 to section 19, and for that half cycle the resonant circuit 92, 93 is supplied with a series of direct current impulses corresponding with the number of segments over which the beam passes. These impulses are integrated on the condenser 93, producing an effect on the circuit 92, 93 similar to that of a single direct current impulse of a duration of one half a cycle of the deflection wave. At the end of this first half cycle, the beam passes from the ring section 19 to section 18 and transmits direct current to the section 18 during the second half cycle without transmitting any current to the circuit 92, 93. Succeeding cycles repeat the performance of the first cycle. The beam thus commutes direct current at the deflection frequency and thereby supplies the necessary control current to maintain the cyclic deflection of the beam. The electrostatic charge collected by the ring section 18, discharges through the high frequency choke coil 98 and the resistance 97 to the battery 53.

At the same time that the beam current is being commutated at the deflection frequency through one set of alternate segments, namely those of the ring 18, 19 in the row 17, 18, 19,

the beam current is also being commutated on the other set of alternate segments, namely those of the ring 17 in the same row, the commutation frequency on the ring 17 segments being higher than the deflection frequency and higher than the frequency of the positive and negative peaks of the deflection control wave. The resulting direct current impulses received on the ring 17 have a constant frequency per second equal to the number, n of segments of the ring 17 in the row 17, 18, 19, multiplied by the deflection frequency, f , or an impulse frequency of nf .

Since the beam may be made to commutate the current abruptly, by sharpening the focus of the beam on the segments, the resulting impulses may be made rich in harmonics of appreciable amplitude. Harmonics of ten or more times the frequency nf may thus be produced in a single commutating operation. By tuning the circuit 81, 82 to resonance with the desired frequency, waves of the frequency nf or of some integral multiple thereof may be selected by transmission to the utilization circuit 84, to the exclusion of wave energy of other frequencies. By making the transmission characteristic of the elements 81, 82, 83 sufficiently broad, several different frequencies may be transmitted to the circuit 84 without changing the impedance adjustment of these elements. When the range of output frequencies is very wide, it is preferable to substitute appropriate reactance and coupling elements 81, 82, 83 for different portions of the frequency range.

The coupling 92, 93 is preferably made loose enough to insure stability of operation of the resonant circuit 92, 93 at the one desired frequency, and to insure the desired constancy of the output frequency. When the uppermost slider 107 is near the upper end of the resistance 104 and the resistance 103 is adjusted to a minimum, and the energy supplied through the secondary coil 99 to the deflectors 6, 7, 8, 9, is insufficient to maintain the desired diameter of circular path of the beam, some increase in energy may be obtained by the expedient of increasing the coupling 92, 93, or by raising the saturation limit of rectifier 90, or by both of these expedients. However, when these expedients are inadequate or are not desired, use may be made of the amplifier 110 by connecting the switch 102, 106 in its lower position, and adjusting the slider 117 until the amplifier 110 provides the desired amount of amplification.

The second and third contacts from the top in the switch 108, in the order named, provide voltages of successive lower strength or value for the deflectors 6, 7, 8, 9 from the second and third sliders 107, respectively of the potentiometer 104. When the switch 108 is in its second position from the top, the associated or second slider 107 is adjusted to make the beam trace its path over the row 15, 16, 17 to produce in the output circuit 80, impulses and waves of a frequency equal to the deflection frequency multiplied by one-half the number of segments in the row. When the switch 108 is in its third position, the third slider 107 is adjusted to make the beam travel wholly over the sectors 15, 16, which serve as a two segment commutator to produce waves of the deflection frequency in the utilization circuit 126 and on the deflectors 6, 7, 8, 9. By transferring the switch 108 from second to third position, it will be seen that output current energy ceases to be transmitted to the output circuit 80. For each position of the switch 108 and of 75

the associated slider 107, the associated phase shifting reactance 108 is adjusted to give the deflector control circuit as a whole, the desired phase angle, as described above in connection with the adjustment of the first or uppermost reactance 108. During the adjustment of the circuits of the second and third contacts of switch 109, the resistance 108 remains unchanged. It is now possible to shift the path of the beam quickly from one row of segments to another and thus select by the switch 109, any one of several different frequencies for production without changing the tuning of the resonant frequency determining circuit 82, 83.

Since the circuit 81, 82 does not control the frequency of commutation, the tuning thereof need not be as critical as that of the circuit 82, 83, and the circuit 81, 82 may therefore be of relatively low cost construction for its particular frequency range.

In order to obtain an output frequency in the range between two adjacent communication frequencies, one of the commutation frequencies, below that of the upper of these two adjacent frequencies, may be employed to produce a harmonic having the desired frequency, or the desired frequency may be obtained by changing the tuning of the circuit 82, 83 to change the beam deflection frequency sufficiently to produce the desired commutation or harmonic frequency. When changing the tuning of the circuit 82, 83, any tendency of the path of the beam to become non-circular may be compensated by adjustment of the impedances 70 in the manner already explained; any tendency of the amplitude of the deflection control wave to depart from its proper value may be compensated by adjustment of the rheostat 103 or the slider 117, and any tendency of the phase angle of the waves on the deflectors 6, 7, 8, 9 to depart from their proper relation to the phase of the wave stored in the circuit 82, 83, may be compensated by adjustment of the reactance 108 or the reactances 108. The reactances 108 and 108, while shown as negative, may obviously be positive.

The range of adjustment of the resonant frequency of the circuit 82, 83 may be made sufficiently wide, with respect to the numbers of segments in the different rows, as to permit of the production, by commutation or by harmonics, of any desired wave frequency between any pair of adjacent output frequencies produced at one deflection frequency, so that any desired output frequency may be obtained in a continuous spectrum extending from the lowest commutation frequency to a frequency many times that of the highest commutation frequency. Because of the fact that the frequency range of adjustment of the circuit 82, 83 may ordinarily be quite limited and in some cases resonance may be permanently fixed at a single frequency, the control circuit elements including the transformer elements 92, 93 and 65, 66, and the impedance elements 70, are adapted for use without replacement while the output frequency is varied from its lower to its upper limit.

More than three contact positions may obviously be provided for the switch 109, together with the associated elements 107, 108, when more than three rows of commutator segments are provided, as in Fig. 6. When rows of successively larger diameter contain respectively larger numbers of segments, the successively higher positions of the switch 109 select successively higher commutation frequencies for production, but in

each of the three or more positions of the switch 109, the wave transmitted to the utilization circuit 120 remains at the deflection frequency.

If it be assumed that there are 200 segments in the row 17, 18, 19 in a particular case, the ring 17 would have 100 segments in that row and the beam current would be commutated at a frequency n_f or 100 f , thereby producing direct current impulses and waves of a frequency of 100 f . The tenth harmonic of the fundamental frequency n_f would have a frequency of 1000 f in the assumed case. If it be further assumed that the deflection frequency determining circuit 82, 83 is made resonant to an audio frequency wave of 1000 cycles, the current would be commutated at a frequency of 100,000 cycles and the tenth harmonic would be 1,000,000 cycles.

It will be understood that the number of segments in any one row may be greater or less than 200 and that the frequency, n at which circuit 82, 83 is resonant may be subaudible, or may be a low or a high radio frequency. Tubes may thus be made to commutate, not only at very low frequencies, but also at extremely high frequencies, and to produce direct current impulses or waves of these frequencies. When the number of segments is considerably less than 200 in one row, very high frequencies may be produced by employing a high deflection frequency.

When very high frequencies are to be produced, it is necessary to use great care in avoiding all unnecessary attention of the impulses and waves. The circuits should be carefully balanced, transmission losses arising from the distributed capacity, inductance and resistance of the high frequency electrodes and of the conductors and couplings extending from these electrodes to the utilization circuit should be reduced to a minimum, and the impedances at the couplings and at the circuit terminations should be matched for efficient operation. Balanced circuits, adapted for high frequency operation, are shown diagrammatically in Figs. 8, 9 and 10 and will be referred to in further detail hereinafter.

Fig. 6 shows the commutator 16 and connected circuits adapted for substitution in Fig. 1 in place of the Fig. 5 arrangement. The commutator has the five ring elements consisting of one set of three sectored elements 15, 16 and 18, 19 and 21, 22, and the intervening alternate set of two closed rings 17 and 20. Five rows of segments are provided, four between the five ring elements, and the fifth consisting of the two sectors 15, 16. Different numbers of segments are provided in each row. It will be understood that the switch 109 in this case has five contact positions, one for each row of segments, so the beam may be deflected over any desired one of the five rows to produce any one of the five different commutation frequencies for a given tuning of the circuit 82, 83.

Rings 17 and 20 are connected with the upper contact of the blade 148 of the two-pole two-position switch 146, 141. Sectors 15, 18 and 21 are connected with the lower contact of the switch blade 146 and with the upper contact of the switch blade 141. Sectors 16, 19 and 22 are connected with the deflection control circuit conductor 85. The switch blade 146 provides an output circuit path through the variable non-inductive resistance coupling element 142 to the positive conductor 82 of the battery 53. The low impedance blocking condensers 143, 144 are connected to transmit impulses, representing the potential difference across resistance 142, to the 75

utilization circuit, UC, 145, by way of the upper contact of the switch 146. The conductor 147, extending from condenser 144 to circuit 145 is grounded at 148.

5 An amplifier A, 149, has its input connected between the condensers 143, 144, and its output connected at one terminal to the lower contact of the switch 146 and at the other terminal to conductor 147. When switch 146 is in its lower position, the amplifier 149 is inserted between coupling 142 and circuit 145 to supply amplified impulses to circuit 145 and to isolate circuits connected with the amplifier output from the coupling circuit 142. Condensers 143 and 144 in conjunction with the ground 148 isolate and safeguard the utilization circuit 145 from static or non-impulsive potentials from the battery 53.

10 The switch blade 140, when in its upper position, connects the output circuit resistance 142 with the closed rings 17 and 20, so that when the beam is deflected over any desired one of the four rows of segments connected with rings 17 and 20, impulses of the corresponding commutation frequency with harmonics thereof are transmitted to the utilization circuit 145. It is thus 15 possible to select any one of a plurality of output frequencies by the switch 160, Fig. 1 while using only a single frequency determining circuit 82, 83, which may be tuned much lower 20 than the output frequency and whose tuning may remain unchanged while the output wave is shifted to any one of several different commutation 25 frequencies extending over a wide range.

30 If desired, the switch 160 may be closed to 35 connect the resonant circuit 161, 162, including the inductance 161 and the variable capacity 162, across the utilization circuit 145, so that some one of the frequency components of the output 40 wave may be selected for transmission to the circuit 145 to the exclusion of all components of different frequency.

45 In its upper position, the switch blade 141 discharges direct current from the sectors 15, 18 and 21 of the commutator, and in its lower position from rings 17 and 20. The direct current path from the blade 141 may be traced through the variable resistance 97, the high impedance choke coil 88 and conductor 82 to the battery 53.

50 When the switch blade 140 is in its lower position, the sectors 15, 18 and 21 of the commutator are connected with the output resistance coupling 142. Two different commutation frequencies are thus supplied simultaneously to the output circuit, one being the deflection frequency 55 and the other being at a higher frequency determined by the rate of travel of the beam over a particular row of segments. The frequency range obtainable with this connection, therefore extends from the lowest deflection frequency to the highest harmonic of the highest commutation frequency. Furthermore, when the output circuit has a broad frequency transmission characteristic, as when the switch 160 remains open and the utilization circuit 145 is not sharply selective, the resulting wave transmitted to the utilization circuit consists of a band of components of different harmonic frequencies, including the fundamental. Since the direct current impulses are cut off during one-half of each successive cycle of the deflection frequency, while the beam is impinging on one of the sectors 16, 19, 22, the output wave band is modulated at the deflection frequency.

70 The Fig. 7 circuit shows how the Fig. 5 circuit 75 may be expanded by adding extra rings to the

commutator, as in Fig. 6. In addition to the output circuit 88, 82, connected with the ring 17, Fig. 5, there is provided in Fig. 7, an output circuit 160, 82, connected with the ring 20. The output coupling 161, 162, included in the output circuit 160, consists of the variable tuning capacity 161 in parallel with the inductance 162, to which is coupled the inductance 163, connecting with the utilization circuit 145. The path of the beam is selected by the switch 160, as already described, so that the beam is deflected over the desired row of segments.

75 It may be assumed that the row 15, 16, 17 contains $2m$ segments and that the rows of successively larger diameter contain, respectively, $2n$, $2p$ and $2q$ segments. The output coupling 81, 82 may then receive impulses having a commutation frequency of either mf or nf , depending on whether the beam traverses the inner or outer row of segments of the ring 17, the deflection 20 frequency being represented by f . Similarly, when the beam travels over the inner or outer row, respectively, of the ring 20, impulses having a commutation frequency of pf or qf , respectively, are transmitted to the output coupling 161, 162. Circuits 81, 82 and 161, 162 are preferably 25 tuned to the frequency of the desired waves, which may be either a commutation frequency or a harmonic thereof, but if desired these circuits may be adjusted to have broad frequency transmission characteristics to permit of the simultaneous transmission of two or more components of different frequency.

30 The output channel 88, 81, 82, 84, or the output channel 160, 161, 162, 164, may be selected to 35 be energized by output waves, or to be deenergized, by merely operating the switch 160 to shift the beam to the desired output channel while the channel 85, 126 remains energized, or channels 84 and 164 may remain deenergized when 40 the switch 160 is in its lowest position, to confine the beam to a path over the sectors 15, 16 and to confine the transmission of waves to the output channel 85, 126. It will be understood that the waves transmitted to the different channels 84, 164 and 126 may each be of a different frequency when their respective commutation frequencies are different, or may be of the same frequency when their respective commutation frequencies are the same.

45 Fig. 8 shows a commutator 170 and connected circuits adapted for substitution in Fig. 1 in place of the Fig. 5 arrangement. The Fig. 8 arrangement is particularly adapted for producing ultra-high frequency impulses and waves, although it may also be employed for producing impulses of any lower frequency. The central disk 171, 172 differs from the disk 15, 16, Fig. 5, merely in having one sector 171 larger in angular measure than the other sector 172. The ring 17 surrounding the central disk, as in Fig. 5, has segments on its edge fitting between alternate segments on the circular rim of the disk 171, 172, as described in detail in connection with the ring 17 and disk 15, 16, Fig. 2. The small sector 172 may have one or more segments on its edge, depending upon the angular widths of the sector and of the segments.

50 The balanced U-shaped coupling circuit 173, 174, has one free end of the U connected with the ring 17 and the other free end connected with the larger sector 171. Length varying means, such as the U-shaped slides 175, are provided in each arm of the U-circuit 173, 174 to adjust the wave length or tuning and the 55 70 65 75 80 85 90 95 100

balance of the circuit at the desired commutation or harmonic frequency. The middle point of the base of the U of the circuit 173, 174, is connected with the positive potential direct current supply lead 82. The smaller sector 172 connects with the deflection control conductor 85. Impulses of direct current, representing commutation at the deflection frequency, are collected on the sector 172 and transmitted over the conductor 86 to the circuit 82, 83, Fig. 1. The utilization circuit UC, 178, is connected through the low impedance blocking condensers 180, 186, with the variable coupling points 181, 181, near the base of the U of the output coupling 173, 174. Waves of the desired commutation or harmonic frequency, for which the coupling 173, 174 is adjusted, are transmitted to the utilization circuit 178.

By reducing the angular width of the sector 172 as much as possible, in terms of the number of segments thereon, the sector 171 and the number of segments thereon may be made correspondingly larger, so that the duration of the interruption of the train of impulses while the beam is on the segment or segments of the sector 172, is correspondingly minimized.

Fig. 9 shows a commutator 188 and connected circuits adapted for substitution in Fig. 1 in place of the Fig. 5 arrangement. The ring 17 surrounds the equal sectors 18, 16, as in Fig. 2. The circuit is similar to that of Fig. 8, except for the portions of the coupling circuits within the rectangle C. The portion of the coupling circuit within the rectangle C, includes in each arm 173, 174, a lumped variable tuning capacity 185 in parallel with a lumped inductance 186 which take the place of the distributed capacity and inductance in the corresponding arms 173, 174 in Fig. 8. The junction of the two seats of elements 185, 186, Fig. 9, connects with the positive direct current supply lead 82. The inductance 187, coupled with the inductances 186, 186, connects with the utilization circuit UC, 178 and transmits waves of the selected output frequency thereto.

Each circuit 185, 186 is preferably tuned to the same desired output frequency which may be either the commutation frequency or a harmonic thereof. The Fig. 9 circuit C is intended more particularly for use at lower frequencies than the Fig. 8 circuit C, but it is to be understood that the circuits C of Figs. 8 and 9 may be interchanged to adapt the Fig. 8 arrangement for the production of lower frequencies or the Fig. 9 arrangement for the production of higher frequencies.

Fig. 10 shows a commutator 198 and its connected circuits for substitution in Fig. 1 in place of the Fig. 5 arrangement. While the arrangements of Figs. 5, 6, 7, 8 and 9 are adapted for either self excitation or separate excitation by the independent source 180, Fig. 1, the Fig. 10 arrangement is adapted only for separate excitation. The switch 86, 87, is placed in its upper position, Fig. 1, so that waves from the source 180 supply a train of direct current impulses to the resonant circuit 82, 83, by rectification in the rectifier 88, the circuit 82, 83 being tuned to the frequency of the source 180 or to a harmonic thereof. The rectifier 88 limits the amplitude of the impulses and the excitation of the circuit 82, 83, thus maintaining the amplitude of the control waves supplied to the deflectors 6, 7, 8, 9 substantially constant, so that the deflections of the beam are kept in their predeter-

mined path when fluctuations of the source 180 tend to make the beam depart from its desired path.

The commutator 198 has the central disk 191 and the coaxial rings 192 and 193 having segments on their adjacent circular edges, as described with reference to the segments on the circular edges of the disk 15, 16, the ring 17 and the ring 18, 19, Fig. 2. The switch 199, Fig. 1, is positioned to select the desired row of segments to be traversed by the beam. When the row 192, 193 is selected and the switch 195 is in its upper position, a continuous train of impulses are transmitted to the two output conductors 196 and the coupling circuit C which may be like the circuit C of either Fig. 8 or Fig. 9. The resulting waves are transmitted from the circuit C to the utilization circuit 178. When the row 191, 192 is selected by the switch 199, the switch 195 is placed in its lower position to connect with the disk 191, so that the output conductors 196 receive impulses from the segments in the row 191, 192.

The arrangements of Figs. 8, 9, and 10 are similar in having balanced circuits and in being operable in push-pull relation in which on the average more than one impulse is received during each commutation cycle of the output wave above the deflection frequency, whereas the arrangements of Figs. 5, 6, and 7 are of simpler construction without balancing of the kind used in the arrangements of Figs. 8, 9, and 10, and the output circuits of Figs. 5, 6, and 7 receive only one impulse during each commutation cycle of the output wave above the deflection frequency.

In the arrangement of any of the above described figures, the beam of electric carriers may consist of carriers other than electrons per se, since the desired relation of the focus to the commutator, and the deflection and commutation of the beam may be obtained with a beam of electric carriers other than simple electrons. Furthermore, one or both of the two electrostatic fields of the two sets of deflecting electrodes 6, 7, and 8, 9, may be replaced in well known manner by magnetic fields adapted to produce the cyclic deflection of the beam.

Any number of rows of segments may be provided in the commutator of any of the above described figures, one row or the minimum number of rows being preferable to a larger number of rows when electrostatic capacity across the output circuit is to be minimized, as in the case of the production of very high frequencies.

A circular path of deflection of the beam has been described and is preferred for many purposes, since it is easier to construct a commutator having sufficiently accurate dimensions and the output frequency is less likely to be variable when the path is circular. Many of the features of the invention may be employed, however, when the cyclic path traced by the beam is of some other shape than circular. It will be seen that the circular path is merely one species of an ellipsoidal path, and that another species of the ellipsoidal path is a linear path. In any case where uniform frequency is desired, any one segment in a given row should be of such length along the path traced by the beam, relative to the rate of movement of the beam when over that segment, that the beam traverses that segment in the same length of time that is required to traverse each other segment in the row at a given deflection frequency.

The angular measure of the sectors 15, 16, or 18, 19, or 21, 22 of Figs. 5, 6, 7, and 9, may be made unequal in the manner shown by the unequal sectors 171, 172, Fig. 8, and may have any other relative angular measure, provided there is a difference between the number of impulses transmitted to the circuit 92, 93 in successive half cycles of the deflection control frequency to which the circuit 92, 93 is tuned. Viewed from another aspect, the deflection frequency may be supplied to the circuit 92, 93, if the impulses transmitted thereto are derived from less than all of one set of alternate segments in the row.

When the source of energy 53 is adjusted to vary the output energy, or when the source 53 departs from its desired potential, or when certain other changes such as load and impedance variations occur in the circuit, the amplitude limiting device 90 tends to stabilize the operation of the system at the desired commutation frequency, so that the beam is kept directed over the desired row of segments.

When commutating the beam current to produce impulses of a desired frequency higher than twice the deflection frequency, the production of impulses of unwanted lower frequencies is avoided within the range between the deflection frequency and the desired higher impulse frequency, in contrast with the production of such lower frequency impulses in systems utilizing a plurality of small harmonic producing stages in cascade. Losses incident to the production of these intermediate frequencies may thus be avoided, and the impulses of desired frequency, produced in accordance with the present invention, may at the same time be of greater energy for a given input energy than in such a cascade system.

What is claimed is:

1. The method of producing electric impulses, which comprises producing a space discharge in the form of a beam of electric carriers, periodically deflecting said beam over any chosen one of a plurality of predetermined paths, causing the deflecting beam to commutate electric current in said chosen path at a predetermined frequency, and utilizing the beam simultaneously to commutate current at a different predetermined frequency.

2. The method which comprises producing a space discharge in the form of a beam of electric carriers, utilizing a control wave of predetermined frequency for periodically deflecting the beam, utilizing the deflecting beam to commutate current at a frequency higher than that of the positive and negative peaks of said control wave, and deriving said control wave from said deflecting beam.

3. The method which comprises producing a space discharge in the form of a beam of electric carriers, utilizing a control wave of predetermined frequency for rotating one end of the beam over a predetermined path, utilizing the rotating beam to commutate current at a frequency higher than that of the positive and negative peaks of said control wave, and deriving said control wave from said deflecting beam.

4. The method which comprises producing a space discharge in the form of a beam of electric carriers, periodically deflecting the beam, deriving from the deflecting beam a current commutated at a predetermined frequency, deriving from said commutated current a wave of frequency lower than said predetermined frequency, and

utilizing said lower frequency wave to produce said periodic deflections of the beam.

5. The method of transmitting waves to a plurality of circuits, each selective to a different frequency, which comprises producing a beam of electric carriers, periodically deflecting the beam, and utilizing the deflecting beam to transmit current by commutation simultaneously to each of said circuits at a frequency of commutation in each respective circuit equal to the frequency for which the circuit is selective.

6. The method of transmitting waves to a plurality of circuits, each selective to a different frequency, which comprises producing a beam of electric carriers, periodically deflecting the beam, utilizing the deflecting beam to transmit current by commutation simultaneously to each of said circuits at a frequency of commutation in a first of said circuits equal to the frequency for which said circuit is selective and at a frequency of commutation in a second of said circuits which is a submultiple of the frequency for which said second circuit is selective.

7. The method of transmitting waves to a plurality of circuits, each selective to a different frequency, which comprises producing a beam of electric carriers, periodically deflecting the beam, utilizing the deflecting beam to transmit current by commutation simultaneously to each of said circuits at a frequency of commutation in each respective circuit equal to the frequency for which the circuit is selective, and utilizing the current commutated at one of said frequencies to produce the periodic deflections of the beam.

8. The method which comprises producing a space discharge in the form of a beam of electric carriers, periodically deflecting the beam, deriving a series of electric impulses from the beam during a portion of each cycle of deflection of the beam, the impulses in each series having a predetermined frequency, converting said impulses into a wave of frequency lower than said predetermined frequency, and utilizing said lower frequency wave to periodically deflect the beam.

9. In combination with a plurality of circuits, each selective to a different frequency, means for producing a beam of electric carriers when suitably energized, means responsive to an electric wave for periodically deflecting the beam, and means including a commutator for transmitting current simultaneously to each of said circuits from the deflecting beam at a frequency of commutation in each respective circuit equal to the frequency for which the circuit is selective.

10. In combination with a plurality of selective circuits, means for producing a beam of electric carriers when suitably energized, means responsive to an electric wave for periodically deflecting the beam, means including a commutator for transmitting current simultaneously to said circuits from the deflecting beam at different frequencies of commutation, one of said circuits being selective to current commutated at one of said frequencies, and another of said circuits being selective to a harmonic of one of said frequencies at which commutation takes place but non-selective at all said commutation frequencies.

11. In combination, a space discharge device having means for producing a beam of electric carriers when suitably energized, an input circuit for periodically deflecting the beam in response to current of predetermined frequency, an output circuit, means including a commutator whereby the deflecting beam commutates current at a frequency higher than that of the positive and nega-

- tive peaks of said deflecting current and whereby said commutated current is transmitted to said output circuit, said output circuit being selective to a component of said higher frequency current, 5 a frequency determining element selective to said predetermined frequency and coupled with said input circuit, and means for deriving impulses of said predetermined frequency from said deflecting beam and for transmitting said impulses to said frequency determining element.
- 10 12. In combination, a space discharge device having means for producing a beam of electric carriers when suitably energized, means responsive to a periodic current for deflecting the beam, 15 means including a commutator for deriving from the deflecting beam a current commutated at predetermined frequency, means for deriving from said commutated current a current of frequency lower than said predetermined frequency, and 20 means for transmitting said current of lower frequency to said deflecting means.
13. In combination, a space discharge device having means for producing a beam of electric carriers when suitably energized, means responsive to an electric wave for periodically deflecting the beam, means for deriving a series of electric 25 impulses from the beam during a portion of each cycle of deflection of the beam, the impulses in each series having a predetermined frequency, 30 means for converting said impulses into a wave of frequency lower than said predetermined frequency, and means for transmitting said lower frequency wave to said deflecting means.
14. In combination, a space discharge device 35 having means for producing a beam of electric carriers when suitably energized, means responsive to an electric wave for periodically deflecting the beam, means for deriving electric impulses of predetermined frequency from the deflecting beam and for utilizing said impulses, means for deriving another set of impulses of said frequency from the beam during a portion of each cycle of deflection of the beam, means for converting said last mentioned impulses into a wave of frequency 40 lower than said predetermined frequency, and means for transmitting said lower frequency wave to said deflecting means.
15. In a wave producer, a space discharge device having means for producing a beam of electric carriers when suitably energized, control means adapted to be energized to periodically deflect the beam over a predetermined path, an output circuit, means for periodically collecting a 45 component of energy from the beam at one frequency and for transmitting said component to said control means, and means for periodically collecting another component of energy from the beam at a higher frequency and for transmitting said higher frequency component to said output 50 circuit.
16. In a wave transmission system, a space discharge device having means for producing a beam of electric carriers when suitably energized, control means adapted to be energized to periodically deflect the beam over a predetermined path, a plurality of output couplings, a commutator having segments disposed in the path of the deflecting beam, one of said output coupling being connected with one set of alternate segments of 55 said commutator, and another of said output couplings being connected with less than all of one set of alternate segments of said commutator.
17. In a wave transmission system, a space discharge device having means for producing a beam of electric carriers when suitably energized,
- control means adapted to be energized to periodically deflect the beam over a predetermined path, a plurality of output couplings, a commutator having segments disposed in the path of the deflecting beam, one of said output coupling being connected with one set of alternate segments of said commutator, another of said output couplings being connected with less than all of one set of alternate segments of said commutator, and means for transmitting current from said last mentioned output coupling to said control means for maintaining the periodic deflection of the beam.
18. In a wave producer, a space discharge device having means for producing a beam of electric carriers when suitably energized, a commutator having segments, a controller responsive to alternating current for periodically deflecting the beam over said segments, a first output circuit connected with certain of said segments, means for transmitting control impulses from said output circuit to said controller, and a second output circuit differently connected with certain of said segments for receiving impulses of a frequency differing from the frequency of deflection of said beam.
19. In a wave transmission system, a space discharge device having means for producing a beam of electric carriers when suitably energized, a commutator having a plurality of rows of segments, control means adapted to be energized to periodically deflect the beam over any one of said rows, output connections for said segments, means for selectively determining the row of segments over which the beam is to be deflected, and means responsive to energy to be transmitted to said control means for maintaining the deflections of the beam over said selected row when fluctuations of said energy tend to make the deflections depart from said selected row.
20. In a wave producer, a space discharge device having means for producing a beam of electric carriers when suitably energized, said device having a beam deflecting circuit and having an output circuit through which current from the beam is periodically transmitted, said output circuit having a coupling with said deflecting circuit, and means responsive to the beam current periodically transmitted through said output circuit for preventing the wave transmitted through said coupling to the deflecting circuit from departing from a predetermined amplitude.
21. In a wave transmission system, a space discharge device having means for producing a beam of electric carriers when suitably energized, a commutator having a row of segments, control means adapted to be energized by a wave for periodically deflecting the beam over said row of segments, and means responsive to the wave to be impressed on said control means for preventing the amplitude of said wave from departing from a predetermined value.
22. The method of translating electric waves which comprises producing impulses, preventing said impulses from departing from a predetermined amplitude, storing said impulses by resonance, controlling the deflections of a beam of electric carriers in accordance with the resulting resonant waves, and commutating direct current under the control of the deflections of the beam.
23. The method which comprises producing a space discharge current, periodically deflecting the space discharge current, storing energy in the form of waves under the control of said deflected current, preventing the amplitude of the current

being stored from departing from a predetermined value, and controlling said periodic deflections in accordance with said stored waves.

24. The method of producing electric waves which comprises producing a space discharge current, periodically transmitting at least a part of said current in the form of impulses, preventing the amplitude of said impulses from departing from a predetermined value, storing energy from the resulting impulses by resonance, and utilizing the resulting resonant waves to control the production of said periodic impulses.

25. In a wave transmission system, a space dis-

charge device having means for producing a beam of electric carriers when suitably energized, a commutator having a row of segments, output connections for said segments, means adapted to be energized by an electric current to cause the beam to be periodically deflected in a predetermined path over said row of segments, and means for maintaining the deflections of the beam within said predetermined path when fluctuations of the energizing current tend to make the beam trace a different path.

JUSTIN L. FEARING.

CERTIFICATE OF CORRECTION.

Acting Commissioner of Patents.

being stored from departing from a predetermined value, and controlling said periodic deflections in accordance with said stored waves.

24. The method of producing electric waves which comprises producing a space discharge current, periodically transmitting at least a part of said current in the form of impulses, preventing the amplitude of said impulses from departing from a predetermined value, storing energy from the resulting impulses by resonance, and utilizing the resulting resonant waves to control the production of said periodic impulses.

25. In a wave transmission system, a space dis-

charge device having means for producing a beam of electric carriers when suitably energized, a commutator having a row of segments, output connections for said segments, means adapted to be energized by an electric current to cause the beam to be periodically deflected in a predetermined path over said row of segments, and means for maintaining the deflections of the beam within said predetermined path when fluctuations of the energizing current tend to make the beam trace a different path.

JUSTIN L. FEARING.

CERTIFICATE OF CORRECTION.

Patent No. 2,124,973.

July 26, 1938.

JUSTIN L. FEARING.

It is hereby certified that error appears in the printed specification of the above numbered patent requiring correction as follows: Page 3, first column, line 61, for "Degassing" read Degassing; page 5, second column, line 22, for the word "by" read for; page 6, first column, line 22, for "communication" read commutation; and second column, line 32, for "attention" read attenuation; page 8, first column, line 39, for "seats read sets; and that the said Letters Patent should be read with this correction therein that the same may conform to the record of the case in the Patent Office.

Signed and sealed this 13th day of September, A. D. 1938.
